UNITED STATES PATENT OFFICE.

HORN G. DONIGAN, OF ST. LOUIS, MISSOURI.

BLOWTORCH.

Application filed March 6, 1920. Serial No. 363,869.

To all whom it may concern:

Be it known that I, HORN G. DONIGAN, a citizen of the United States, residing at the city of St. Louis and State of Missouri, have invented a new and useful Blowtorch, of which the following is a specification.

This invention relates to improvements in blow torches, and consists in the novel construction hereinafter disclosed.

10 An object of the invention is to provide a blow torch for welding metals, and other purposes, designed to effect a perfect mixture of the gases, and to prevent back fire in the gas passages.

15 Additional advantages of the construction will be apparent from the detailed description of the invention taken in connection with the accompanying drawing, in which

Fig. 1 is an elevation showing the torch construction.

Fig. 2 is a vertical section through the head of the torch.

Fig. 3 is a cross section taken substantially on the line 3-3 of Fig. 2.

25 The invention as illustrated in the drawing is shown as including a handle section which may be of any suitable form, but preferably in the form of a casting having separate passageways 2 and 3 respectively

30 therethrough, said passageways being controlled by valves 4 and 5 respectively. The passageway 2 constitutes a conduit for one of the gases for instance, in an oxygen acetylene torch, a passage for the oxygen; the gas 35 being supplied thereto through a flexible tube 6 connected with the source of supply. The passage 3 constitutes a conduit for the other gas, that is in an oxygen acetylene torch, a passage for the acetylene; the gas 40 being supplied through a flexible tube 7 connected into the end of the passage 3.

A tube 8 connects with the front end of the passage 2 and extends forwardly some distance of the handle, and a tube 9 connects into the forward end of the passage 3 and extends forwardly some distance of the handle. It will be understood that the volume and pressure of the gases may be independently controlled by means of the 45 valves 4 and 5.

The head of the torch includes a tubular cylindrical casing 10 provided with hollow bosses 11 and 12, the passage ways 13 and 14 through the bosses 11 and 12 constituting

50 inlet openings for the passage of the gases into the mixing chamber. The passages 13

and 14 are preferably arranged in vertical alinement and spaced apart, the upper passage entering the casing 10 near the top thereof, and the passage 14 entering the 60 casing at some distance below the passage 13.

A hollow stem 15, constituting a nozzle, is adapted to be inserted in the lower end of the casing 10, and to be held in place 65 therein by threaded engagement, the upper head 16 of the stem being externally threaded to fit an internally threaded portion 17 of the casing 10.

It will be observed that when the stem 15 70 is in place the upper end thereof terminates slightly below the opening 13, so that there will be a free passage of the gas through the opening 13 into the nozzle passage 18. The stem 15 is provided with a flange 19 that has 75 its upper face beveled to form a cone seat so that a tight joint will be effected at the lower end of the chamber 10 when the stem 15 is screwed in place. The stem 15 at its lower extremity is provided with an exteriorly threaded portion 20 for receiving a 80 removable torch tip 21, it being understood that varying types of tips may be applied to the torch.

The upper end of the chamber 10 is closed 85 by a removable screw plug 22 that threads into the upper end of the chamber 10. The screw plug 22 has a flange 23 that fits tightly against the upper end of the chamber providing a sealed ground joint preventing the escape of the gas from the mixing chamber. The lower face of the screw plug 22 is preferably provided with a concave recess 24, thereby forming a chamber above 90 the inlet opening 13. Thus, whenever there is an obstruction at the outlet end of the torch the column of gas admitted through the opening 13 will cushion back into the chamber above the opening and prevent back fire in the conduit 8.

100 The stem 15 has a recessed portion 25 so that a chamber is formed between the inner wall of the casing 10 and the stem at a point substantially midway of the length of the chamber 10. The chamber thus formed is 105 in registration with the inlet opening 14. The gas from the conduit 9 enters this chamber and passes therefrom through openings 26 into the passage 18 at a point some distance below the top thereof.

110 In practice for welding operations, the torch is preferably supplied with a mixture

of oxygen and acetylene gas, although it will be understood that it is not limited to the use of such gases. The column of oxygen gas enters from the conduit 8 through the passage 13, the pressure being regulated according to operative requirements by the valve 4. The column of gas passes through the opening 18 having an aspirator or suction effect, causing at least a partial vacuum in the chamber 24 above the inlet 13. The acetylene gas is admitted through the passage 14 into the chamber formed by the recess 25, from whence it passes through the ports 26 thoroughly mixing with the incoming column of the oxygen gas as it passes the ports 26. Thus the two gases are thoroughly mixed producing a combustive mixture that burns with a flame of high degree of heat at the tip. If, by any reason, the outlet or tip is obstructed, the incoming column of oxygen above the inlet of the acetylene prevents any back-fire into the gas conduits.

I am aware that the invention may be modified in certain particulars without departing from the spirit and scope of the invention. I do not limit myself therefore to the exact construction and arrangement shown and described, but what I claim and desire to secure by Letters Patent, is:—

1. A blow torch, comprising a casing, a gas inlet tube connected with and opening radially into said casing adjacent to one end thereof, an additional gas inlet tube connected with and opening radially into said casing between the first tube and the opposite end of the casing, threads formed on the inner wall of the casing between said tubes, a stem extending into the casing and terminating between said two inlet tubes, a removable plug extending into the casing

and having its end in alinement with and spaced from said stem, threads on the inner end of said stem engaging the threads in the casing, a flange on said stem engaging the end of the casing and limiting inward movement of the stem into the casing, a chamber between said stem and the wall of the casing in communication with the second inlet tube, a passage through the stem in communication with the first inlet tube, and passages through the wall of the stem forming communications from said chamber to the passage through the stem.

2. A blow torch, comprising a casing, a gas inlet tube opening into said casing adjacent to one end thereof, an additional gas inlet tube opening into said casing between the first tube and the opposite end of the casing, threads formed on the inner wall of the casing between said tubes, a tubular stem extending into the casing and terminating between said tubes, threads on the inner end of said stem engaging the threads in the casing, a removable plug extending into the casing and leaving a radial communication with the first tube from the space between said plug and the end of the stem, an abutment engaging the end of the casing and limiting inward movement of the stem into the casing, an annular chamber between said stem and the wall of the casing in communication with the second tube, radial passages through the wall of the stem forming communications from said chamber to the inside of the stem, and a torch tip removably supported by the outer end of the stem having a passage therethrough in communication with the passage through the stem.

HORN G. DONIGAN.
